TUBULAR ARTICLE FOR DECORATIVE OR STRUCTURAL PURPOSES

Norman A. Groneman, Roselle, and Earl A. Sederberg, Naperville, Ill., assignors, by mesne assignments, to E. L. Reibold Agency, Inc., Chicago, Ill., a corporation of Illinois

Filed Nov. 2, 1959, Ser. No. 850,383
4 Claims. (Cl. 189—34)

This invention relates to a tubular article for decorative or structural purposes, constructed of parts which snap together in assembling the article. The invention is especially useful for aesthetic purposes, employed either alone or as a decorative sheath to impart an attractive appearance to other structural and ornamental members.

Various structures are constructed of exposed or visible structural and ornamental bars, rods, tubes and like members, all referred to herein as bar members or bars. It has been necessary or desirable in many instances to construct these members of materials which are not very attractive by nature, or are difficult to make and keep attractive. For example, tubular steel is widely used in the construction of display fixtures, and a decorative finish may be painted and baked on the surfaces. Such a finish is often easily scratched and worn, and this detracts from the aesthetic effect desired in connection with the merchandise on display. Other materials such as wood and plastics also become damaged or unsightly in use. The various surfaces may be marred by physical contacts, oxidation, or chemical attack. Another disadvantage encountered is that the screws, bolts, and other means used for connecting the members detract from the overall appearance, or special measures are required to conceal or eliminate the connections.

An object of the present invention is to provide a tubular article for decorative or structural purposes, which may be employed as a sheath over a structural member, or which may substitute therefor where structural strength is not a significant factor.

An important object is to provide an article which is easily mounted and located on a structural member, while securely fastened thereto, and then is as easily removed.

Another primary object is to provide an article which presents a very pleasing appearance, is readily constructed and economical, and may be used on various structures to enhance their appearance.

An additional object is to provide an article which conceals the connections to other structure.

A further object is to provide an article which is supplied and constructed as a staple ornamental and structural item, and may be cut to various desired dimensions and assembled to fit the needs of the user.

These and other objects, advantages and functions of the invention will be apparent from the description and from the accompanying drawings, in which like parts are identified by like reference characters in each of the views, and in which

FIGURE 1 is a perspective view of a preferred embodiment of the decorative or structural tubular article of the invention;

FIGURE 2 is an enlarged cross-section of the embodiment of FIGURE 1;

FIGURE 3 is a cross-section of another embodiment of the invention;

FIGURE 4 is a perspective view of the embodiment of FIGURE 1, with a portion broken away, illustrating its assembly with other structure in a display fixture;

FIGURE 5 is an illustration on a reduced scale of the embodiment of FIGURE 1 employed in connection with another type of display fixture;

FIGURE 6 is a perspective view illustrating a T con-

2

nnection made with the embodiment of FIGURE 1; and FIGURE 7 is a perspective view illustrating the construction of an angle with the embodiment of FIGURE 1.

The invention provides a tubular article for decorative or structural purposes which includes longitudinal tube sections that snap together, and mate to form a tube. Flanges are provided on each of the tube sections adjacent their longitudinal edges, and they interlock in snap-fastening engagement. Also provided for decorative or structural purposes is an assembly of a bar member and the tubular article constituting a sheath enclosing the bar member. In the preferred embodiment, the assembly is employed in display fixtures and the like which are viewed by the purchasing public.

15 The preferred embodiment of the tubular article or tube 1, as illustrated in FIGURE 1 of the drawings, is composed of mating longitudinal tube sections 2 and 3. In this embodiment, one section 2 is constructed as a duct or channel having two broad marginal internally flat 20 parallel sides 2b and 2c joined by a perpendicular side 2d, constituting three sides of the tube 1. The mating section 3 constitutes a closure strip for the duct and forms the remaining side of a continuous single-walled square rectangular tube having a tube cavity 1a, the said remaining side being parallel to the duct side 2d. The sections 25 adjoin at two flush joints 4 adjacent the corners along the said remaining side of the tube, so that only fine lines 5 are visible at the junctures, and they are scarcely noticeable. The outer surfaces 2a and 3a of the tube 1 include 30 flutes 6, which enhance the appearance of a unitary tube.

The duct section 2 of the embodiment of FIGURE 1 includes outwardly extending longitudinal continuous flanges 7 at or adjacent its longitudinal edges or said margins. The flanges include narrow longitudinal beads 8 and longitudinal grooves 9 on the respective internal surfaces of the parallel sides 2b and 2c and spaced from the perpendicular side 2d. Similarly, the closure section 3 of this embodiment is provided with outwardly extending continuous longitudinal flanges 10 at or adjacent 40 its longitudinal edges or side margins, which are complementary to the duct section flanges 7. The closure flanges include grooves 11 which receive the beads 8 of the duct flanges, and beads 12 which are received by the grooves 9 of the duct flanges. The flanges 7 and 10 on the respective 45 sections are adapted for snapping together by pressure against opposite sides of the tube, and interlocking to form the flush joints 4 substantially completely lying within the tube wall confines so as not to protrude from the tube wall surfaces. As described above, the provision 50 of the flush joints is an important component of the overall attractive appearance of the article. The interior of the article also has a smooth surface at the joints and throughout, for proper assembly on other bars, and to permit movement of the tubes thereon without interference.

The construction of the snap flanges 7 and 10 also enables one tube section to move longitudinally with respect to the other, in sliding engagement, for adjusting either member as required in connection with associated structure. The sections may also be assembled to form the tube 1 in this manner when possible, but it is often not possible due to interference with associated structure. The construction for snapping the parts together is very important for attaching the tube to structures previously assembled in use. Thus, the tube sections 2 and 3 are adapted for laterally inserting a bar member of approximately the same size and configuration as the tube cavity 1a between their side margins, and for then snapping the sections 65 around such bar member.

A significant advantage of the tubular article 1 is that it may be fabricated conveniently and economically by

extrusion in conventional manner. It also may be constructed in other ways, such as by casting, but extrusion is generally the most advantageous and least costly. The extrusion dies require only the corresponding die openings, and there is no necessity for core means as would be required for extruding a one-piece tube. The preferred embodiment thus is formed as two one-piece continuous extrusions which snap together.

The invention makes it possible at relatively little or possibly no additional cost, to enclose or cover structural or ornamental members with decorative or protective sheathing. The structural framework to be covered may be constructed of bare metal, wood or plastic, saving the labor and expense of imparting an attractive appearance or protective surface thereto. Structures which have been in use and either were not especially attractive originally or have lost their appearance may be enclosed by the tubular article. Their appearance is restored and in many cases becomes much more pleasing.

The preferred article of the invention is constructed of extruded aluminum. The appearance of the exterior surfaces is protected by anodizing them according to standard methods. It is further preferred to add a decorative finish on the anodic oxide layer, also in conventional manner, which is very durable and resistant to physical and chemical forces. In this manner, a very attractive bright finish, such as a gold finish may be imparted to the outer surfaces 2a and 3a, and it is outstandingly superior to the enamel finishes employed on the tubular steel stock which is commonly used. Other colors and types of finishes may be provided as desired. Alternatively, the anodized surface may be sufficient, and no decorative finish need be added.

The methods of anodizing aluminum, i.e., subjecting it to anodic treatment or electrolytic oxidation in a suitable electrolyte so as to secure a dense, adherent coating of aluminum oxide, are well known. Oxide layers on the order of about 0.0002 to 0.0005 inch may be produced. The metal may be pure aluminum or aluminum base alloys, that is, aluminum modified or alloyed with other elements, such as copper, and the term "aluminum" is intended to include both herein.

Other preferably light weight metals and alloys can be used, which preferably are extrudable. The metal is selected on the basis of the intended use, cost, and structural strength requirements. It is also possible to use other of the various materials and methods of construction. Depending upon the requirements, the tube 1 advantageously may be constructed of other extrudable and hardenable material, such as synthetic resins or other plastic compositions. Such materials provide very low cost articles where metal articles are not necessary.

The tubular article 1 thus produced may serve for structural or decorative purposes, or both, and may have plain or ornamental surfaces. The article may be employed as a sheath or jacket over other members; it may bridge other members as illustrated in FIGURE 5; or it may be employed alone, especially in primarily ornamental applications.

FIGURE 3 illustrates another very useful embodiment which may be used in like manner. A circular tube 13 is composed of semi-circular longitudinal sections 14 and 15. Integral snap flanges 16 and 17 are formed along the longitudinal edges of the respective sections and interlock at flush joints 18, in like manner to the embodiment illustrated in the remaining views. The external surfaces may include flutes 19, be smooth and circular or have a different contour, such as elliptical. This structure is designed for enclosing circular bar members, such as the circular tube 20 illustrated in phantom in the drawing.

The invention is not limited to the preferred embodiments illustrated, but various changes in structure and arrangement can be made while accomplishing the objects of the invention. For example, the respective flanges 7 and 10 of the embodiment of FIGURE 1 are in

one piece with their tube sections and continuous for the length thereof. The flanges alternatively may be made discontinuous and non-integral, although such construction is less desirable. The contours and arrangements of the flanges may be altered. The cross-section or shape of the article may be varied substantially as desired; e.g., it also may be rectangular, hexagonal, elliptical, or other configuration. The external surfaces may be contoured as desired.

10 When the tubular article such as 1 or 13 is employed as a sheath for a bar member, such as the tube 20 illustrated in FIGURE 3 or the tube 21 illustrated in FIGURE 1, the inside dimensions of the sheath tube preferably are slightly greater than the corresponding outside dimensions of the bar member which is enclosed. Consequently, a small space remains between the outer walls of the bar member and the inner walls of the sheath, as illustrated at 22 in FIGURE 1. This space serves to accommodate projecting screws, bolts, other fastening means, or surface irregularities on the enclosed bar member 21 or like. The tubular articles are also free to move longitudinally on the enclosed bar members. This additional space need not be provided in many instances, so that the articles fit together. The tubular article 1 having a square rectangular tube cavity 1a thereby is mounted on the rectangular bar member 21 having approximately the same size and configuration as the tube cavity, so that relative rotational movement between the tubular article and the bar member is substantially prevented.

20 FIGURES 4 and 6 illustrate connections to additional structure, employing screws or a bolt, respectively. In FIGURE 4, a portion of a display fixture is illustrated, which includes a display arm 23 secured by means of screws 24 to a tubular structural bar 25 having holes 35 drilled therethrough for accommodating the screws. In this case, flat head screws are used and they are flush with the outer surface of the bar 25. At other times, the round head screws might be used, so that the space 26 between the tubular members would be necessary.

30 In this assembly, the closure member 3 for the duct 2 is also secured to the display arm 23, between it and the bar 25, and the screws 24 pass through holes provided in the closure member. The duct section 2 of the tube can be snapped in place on the closure 3 and removed therefrom as desired. The fastening connections are hidden from view, and therefore an attractive appearance is presented. In an alternative arrangement, where the structural strength requirements are not excessive, only the new tubular article 1 might be employed. In such case, the display arm 23 may be secured directly to the closure section 3, with the heads of the screws 24 enclosed within the article, or the arm may be similarly fastened to the opposite side of the duct section 2.

40 Another arrangement which can be provided with a display case is illustrated in FIGURE 5. This view illustrates a wood panel portion 27 of a display case supported by a bar member leg 28 joined to a rounded base or pedestal 29. Previously, the supporting bar 28 may have extended to a point above the wood panel 27. By employing the present invention, an upper post 30 may be used instead of a long bar member, and the supporting bar and the post enclosed within the tubular article 1 to present the attractive appearance desired. In this arrangement, one continuous duct section 2 of the tube extends from the pedestal 29 to a decorative top piece 31 secured to the upper post 30. Upper and lower portions of the duct section 2 are secured to the closure sections 3, which abut on the panel 27. This illustrates the adaptability of the two-piece tube 1, and its advantageous assembly on a structure. The duct section 2 can also be employed alone to enhance the appearance along the edge of a panel or the like. For example, it can be placed over the lower edge 32 of the panel 27 with the edge of the panel received in the duct and embraced by the sides 2b, 2c and 2d, for decorative effect.

FIGURE 6 illustrates one manner in which connections in a structure can be enclosed by the new tubular articles. This view illustrates a T connection between structural tube members 33 and 34 normal to each other. One member 33 is provided with holes through opposite sides, which serve as means for connecting the member to other structure. The structural members are connected by a bolt 35 which extends through the holes in the one member 33 and is received in a nut 36 secured within the other member 34. The latter member is enclosed by a length 10 of the sheath tube 1, which abuts on the former member 33. This member 33 is enclosed within another length of the duct section 2, and lengths of the closure section 3 cover the member up to the adjoining sheath tube 1, where the ends of the closure section lengths about opposite sides thereof. An attractive appearance is achieved, and the sheath tube parts are easily secured and removed.

FIGURE 7 is an illustration of the invention applied to a corner or elbow in a structure, wherein bars 37 and 38 meet at a right angle, although the angle could be different. The area corresponding to the end of one bar member 37 is covered by an extending portion 39 of the closure section 3. In order to achieve a close fit, the flanges 10 of the closure member are omitted or severed for a distance equal to the depth of the duct 2. In covering structures meeting at other angles, it is only necessary to cut the parts of the tube 1 at appropriate angles.

In this manner, the invention is useful for numerous structural and ornamental purposes. The construction is easily and rapidly assembled, and material, manufacturing and labor costs are relatively low. By employing the new tubular article as a sheath, the advantages of other materials of construction are obtained together with the advantages of the invention. There are also many instances where the tubular article may be used alone to advantage, or part of the structure which would otherwise be included, can be eliminated. The invention is very useful in restoring or improving the appearance of structures already in use, and it also eliminates the need for finishing operations on parts of structures being fabricated. The improvements are especially desirable as applied to display racks, showcases, receptacles, tables and other merchandising structures viewed by the public. It is advantageous to the supplier and to the user that the tubular articles can be manufactured in large or small quantities and in many sizes and shapes, and a quantity can be maintained in stock and immediately cut to size and assembled when and where the need arises.

The invention is hereby claimed as follows:

1. A tubular article for decorative or structural purposes constructed in two sections which are adapted to be snapped together on a bar member to enclose the same and present an external substantially joint-free appearance, and one of which sections is adapted for receiving a panel edge or the like therein whereby it may be employed alone as an edge trim,

which comprises a pair of mating longitudinal tube sections each having two longitudinally extending side margins, said sections uniting along said side margins to form a continuous single-walled tube having external and internal wall surfaces, said internal wall surface defining a rectangular tube cavity in cross section,

one of said sections having two broad marginal internally flat sides respectively terminating in said side margins of the section,

means providing a narrow longitudinal groove on the internal surface of each of said sides adjacent said side margin thereof, said one section thereby being adapted for receiving a panel edge or the like therein and embraced by said sides,

a longitudinal bead extending outwardly from the remaining one of said sections adjacent each side margin thereof and being received in one of said grooves in interlocking engagement, whereby said sections are united at points substantially completely lying within the tube wall confines so as not to protrude from said wall surfaces,

said beads and groove means forming junctures which appear only as scarcely visible fine lines on said external surface, said sections being united by pressing them together at said joints,

thereby causing said beads and groove means to snap together into interlocking engagement,

and said sections thereby being adapted for laterally inserting a rectangular bar member of approximately the same size and configuration as said tube cavity between their side margins, and for then snapping the sections together around such bar member, whereby relative rotational movement between such bar member and the tubular article about a longitudinal axis is substantially prevented.

2. A tubular article as defined in claim 1 wherein said one section comprises a channel and said sides thereof are parallel and joined by a side perpendicular thereto, and said remaining section comprises a closure strip providing a side on the tube parallel to said perpendicular side.

3. An assembly for decorative or structural purposes of a tubular article as defined in claim 1, and a rectangular bar member having approximately the same size and configuration as said tube cavity and enclosed by said tubular article.

4. An assembly for decorative or structural purposes of a tubular article as defined in claim 1, and a display fixture including a rectangular structural bar member having approximately the same size and configuration as said tube cavity, said bar member being enclosed by said tubular article.
